UNITED STATES PATENT OFFICE.

FRITZ FINCKH, OF ESSEN, GERMANY, ASSIGNOR TO FRIED. KRUPP AKTIENGESELLSCHAFT, OF ESSEN-ON-THE-RUHR, GERMANY.

OPERATING MECHANISM FOR THE DOORS OF SELF-DISCHARGING RECEPTACLES.

1,421,439.

Specification of Letters Patent.

Patented July 4, 1922.

Application filed June 2, 1921. Serial No. 474,532.

To all whom it may concern:

Be it known that I, FRITZ FINCKH, residing at Essen, Germany, a citizen of the German Republic, have invented a certain new and useful Improvement in Operating Mechanism for the Doors of Self-Discharging Receptacles, of which the following is a specification.

This invention relates to operating mechanisms for working the doors of self-discharging receptacles and the object of the invention is to so arrange operating mechanisms of this kind, that a great effect of force produced by toggle lever action is exerted on the doors over as great an angular path as possible.

In the drawing is shown as an embodiment of the subject-matter of the invention and by way of example, a self-discharging railway car, which has a door bottom which opens in the middle on discharging and in which the operating mechanism forming the subject-matter of the present invention is shown for operating these bottom discharging doors.

Figs. 1 to 3 each show an end view, partially in section, of the self-discharger with the discharging doors and the operating mechanism in different positions.

30 A and B denote the discharging doors of the bottom which doors A and B are to be actuated by the operating mechanism, when the closing movement takes place, and which doors A and B are each pivotally mounted on a shaft c^1 fixed to the frame C of the self-discharger, symmetrically to the central longitudinal plane of the car. These doors A and B are mounted in such way that they tend to assume their open position under the action of the weight of the material contained in the car (see Fig. 2). To the discharging door A are attached several connecting rods D (which cover each other in the drawing) by which the door is connected 45 to crank arms E, which are fixed on a crank shaft E^1 carried on the frame C. On the shaft E^1 there is also mounted a crank arm E^2 , to which one end of a connecting rod F is attached. The other end of this connecting rod F is attached to a crank arm G, which, together with another crank G^1 arranged at right angles to it, is rigidly fixed on a shaft G^2 carried in a bearing bracket C ^{2} . To the crank arm G^1 there is attached 55 a connecting rod H, which connects the said

crank arm G^1 to a crank arm J ^{2} corresponding to the crank arm E ^{2} , and which, together with several crank arms J corresponding to the crank arms E, is mounted on a shaft J ^{1} . The door B is connected to the crank arms 60 J by connecting rods K corresponding to the connecting rods D.

When in the closing movement of the discharging doors A and B, in which movement the shaft G ^{2} rotates in the direction indicated by the arrow x , the closed position shown in Fig. 1 is attained, both the operating crank arm G of the crank gearing G, F, E ^{2} and also the operating crank arm G ^{1} of the crank gearing G ^{1} , H, J ^{2} have passed 65 beyond the dead position. At the same time the operating crank arms E of the crank gearings E, D, which latter act in succession with respect to the crank gearing G, F, E ^{2} on the discharging door A, have also passed 70 beyond their dead position which is denoted by straight line 1—2 (see Figs. 1 and 3). In like manner the operating crank arms J of the crank gearings J, K, which latter act in succession with respect to the crank gearing G ^{1} , H, J ^{2} of the discharging door B, have also passed 75 beyond their dead position which is denoted by a straight line 1'—2'. When in this position of the crank arms E ^{2} and J ^{2} lie each against a stop c^3 on the 80 frame C of the self-discharger, whereby the angle, by which the crank arms E and J have passed beyond their dead positions is limited. The angle by which the crank arms J have passed beyond their dead positions (1'—2') is greater than the angle by 85 which the crank arms E have passed beyond their dead position (1—2) (see Fig. 1). The ratios are further so selected that when the crank arms E are at their dead position 90 the crank arm G is still before its dead position. The same holds good for the crank arms J and the crank arm G ^{1} .

On the shaft G ^{2} there is mounted a hand lever M, which is free to rotate relatively to the shaft within certain limits. These limits are fixed by a crank pin g^4 which is mounted on a crank arm G ^{3} rigidly connected to the shaft G ^{2} . This crank pin g^4 is adapted to engage either in the one or the 100 other of two lugs m^1 and m^2 arranged on the lever M. According as the pin g^4 engages with the lug m^1 or m^2 , the lever M is coupled with the shaft G ^{2} for rotation either in the 105 direction of the arrow x (see Figs. 1 and 3) 110

or in the opposite direction. In the angular position the lever M assumes when it bears with the lug m^1 upon the pin g^4 in the closed position of the discharging doors and of the 5 corresponding crank gears, it can be locked relatively to the frame C by means of a key bolt N.

In the closed position shown in Fig. 1, of the discharging doors and of the corresponding operating mechanisms each of the doors A and B is doubly secured against being automatically opened under the action of the weight of the loaded material, as the dead positions have been passed over both 10 in the crank gears D, E and E^2 , F, G constituting a plural system of dead center locks and also in the crank gears K, J and J^2 , H, G^1 . As the hand lever M is locked by the key bolt N and lies with the lug m^1 upon the bolt g^4 , the doors A and B are also ensured with certainty against being opened under the action of any accidentally occurring external forces, which might possibly cause rotation of the shaft G^2 .

25 For the purpose of discharging, the hand lever M, after the key bolt N has been removed, is rotated in the direction opposite to that of the arrow α . The shaft G^2 remains during this time at rest until the lug m^2 has come into contact with the crank pin g^4 , after which, on the further rotation of the hand lever, the shaft G^2 is also carried along with it. As soon as in this operation 30 the crank arms G and E have passed beyond their dead positions, the weight of the loaded material bearing on the door A forms a driving force for the shaft G^2 , so that the power required to rotate the hand lever M is reduced to a very small amount. After 35 the shaft G^2 has attained an angular position in which also the crank arms J and the crank arm G^1 , which passes through the dead position before them, have passed beyond their dead positions, the weight of the loaded material bearing on the door B forms a driving force for the shaft. As soon as 40 this latter has rotated sufficiently to allow of the pressure of the loaded material tending to open the doors, to overcome the frictional resistances of the operating mechanism, the doors move automatically into the opening position shown in Fig. 2. A jerking action cannot be exerted on the hand lever, as the crank pin g^4 can pass out unhindered 45 from the lug m^2 of the hand lever and consequently the shaft G^2 can move in advance of the hand lever.

To return the discharging doors into the closed position the hand lever is rotated in the direction indicated by the arrow α (Fig. 2). After, in this rotation, the lug m^1 has come into contact with the crank pin g^4 the rotation is transmitted to the shaft G^2 and imparts the closing movement to the discharging doors through the medium of the 50

crank gearings G, F, E^2 and E, D, as also G^1 , H, J^2 and J, K. As in the closed position (see Fig. 1) of the discharging doors the crank arm J has passed farther beyond its dead position than the crank arm E, the result is that before the dead positions are attained, towards the end of the closing movement (see Fig. 3) the angle $2'$, $1'$, $3'$ through which the crank arm J is distant from its dead position is smaller than the corresponding angle 2 , 1 , 3 for the crank arm E (see Fig. 3). The crank gearing J, K, therefore commences to exert a toggle lever action sooner than the crank gearing E, D. Therefore, on the closing movement of the discharge doors even at a comparatively early point of time and over a correspondingly large angular path a strong moment of force produced by toggle lever action through the operating mechanism moving the discharge doors is exerted, whereby the closing of these latter is considerably facilitated. As the driving crank arms G and G^1 of the crank gearings G, F, E^2 and G^1 , H, J^2 reach their dead positions later than the crank arms E and J, they are still so far remote from their dead positions at the commencement of the toggle lever action of the crank gears E, D, and J, K, that they cannot still exert any toggle lever action (see Fig. 90 5). During the further course of the closing movement however, also the crank gearings G, F, E^2 and G^1 , H, J^2 still exert a toggle lever action so that the effect of the operating mechanism is still further increased in correspondence with the resistance which increases as the discharging doors approach the closed position. As soon as the crank arms J have passed beyond their dead position ($1'$ — $2'$) the weight of 95 the door B, while the crank arms J approach their end position fixed by the stop c^2 , acts as a driving factor on the crank arms (see Fig. 1). This driving action is transmitted from the crank arms through 100 the crank gearing J^2 , H, G^1 and G, F, E^2 to the cranks E and consequently, as long as these have not yet passed beyond their dead positions, assists automatically the closing movement of the door A. The closing movement is ended as soon as the operating mechanism has again attained the position 105 shown in Fig. 1 from which the description of the action of the gearing was commenced.

110 I claim:

1. In combination with a door member, a plural system of interconnected dead center locks the one dead center lock actuated by another of the dead center locks above referred to, the one dead center lock reaching a substantially dead center position before its actuating dead center lock.

2. In combination with a door member, a plural system of interconnected dead center 125 130

locks the one dead center lock actuated by another of the dead center locks above referred to, the one dead center lock reaching a substantially dead center position before 5 its actuating dead center lock, and a free abutting means for actuating said plural system of dead center locks.

3. In combination with a car having a plural system of unloading doors, a plural 10 system of interconnected dead center locks for at least two of said doors and a common means for operating said last named plural system of doors and locks according to a predetermined sequence.

15 4. In combination with a car having a plural system of unloading doors, a plural system of interconnected dead center locks for at least two of said doors and a common means for operating said last named plural 20 system of doors and locks according to a

predetermined sequence, said sequence comprising the unlocking of one dead center lock of a given door after the corresponding unlocking of a dead center lock for a previous door. 25

5. In combination with a door member, a plural system of interconnected dead center locks the one dead center lock actuated by another of the dead center locks above referred to, the one dead center lock reaching 30 a substantially dead center position before its actuating dead center lock, and a free abutting means for actuating said plural system of dead center locks, and a further means for locking said door and locks in a 35 given position.

The foregoing specification signed at Es-
sen, Germany, this 18th day of April, 1921.

FRITZ FINCKH.
